UNITED STATES PATENT OFFICE.

EDWARD CRAIG, OF ST. JOSEPH, MICHIGAN, ASSIGNOR TO SARANAC MACHINE COMPANY, OF BENTON HARBOR, MICHIGAN, A CORPORATION OF MICHIGAN.

CARTON-STAPLING MACHINE.

1,280,410.

Specification of Letters Patent.

Patented Oct. 1, 1918.

Application filed July 26, 1915. Serial No. 41,852.

To all whom it may concern:

Be it known that I, EDWARD CRAIG, a citizen of the United States of America, and resident of Niles avenue, St. Joseph, Michigan, have invented a certain new and useful Improvement in Carton-Stapling Machines, of which the following is a specification.

My invention relates to stapling machines of that kind in which the various elements thereof are arranged for stapling together the overlapped portions of a carton blank, the staples being driven in a row close to one corner of the carton, and the flaps at the opposite ends of the carton being left unfolded and open.

Another object is to provide an improved construction and arrangement whereby the staple driver and all of the parts attached thereto are detachable and removable as a unit.

Another object is to provide a staple former and a staple driver of novel construction and formation, the two being cut away to form an interlocking construction, thereby to hold them together, and the spring for the staple former being carried by the driver in a novel and effective manner, as will hereinafter more fully appear.

Another object is to provide improved means for supporting the blank during the stapling operation, of such character that the adjustment of the table or work support will automatically change the position of the anvil or clenching device, whereby independent adjustment of said device will not be necessary.

Another object is to provide an improved construction and arrangement whereby no hanger or body support will be necessary for the guide by which the carton blank is guided to the stapler, so that clearance will be provided for the manipulation of the carton blank, and to avoid the use of certain devices and features of construction heretofore considered necessary.

It is also an object to provide certain details and features of construction and combinations tending to increase the general efficiency and desirability of a stapling machine or stitcher of this particular character.

To these and other useful ends my invention consists in matters hereinafter set forth and claimed.

In the accompanying drawings—

Figure 1 is a side elevation of a stapling machine or socalled stitcher embodying the principles of my invention.

Fig. 2 is a section on line 2—2 in Fig. 3.

Fig. 3 is a plan view of a portion of the carton, and the adjacent portions of the table and yielding plate for supporting the clenching device, illustrating the method of feeding the blank over the table and support to the stapler.

Fig. 4 is a vertical longitudinal section of the stapling head.

Fig. 5 is a perspective of one of the carton blanks after being stapled together at one corner thereof.

Fig. 6 is a front elevation of the springy or resilient support for feeding the carton blank to the stapler, said support having the clenching device yieldingly mounted thereon, whereby said clenching device is thrust downward by the staple driver until the pressure is resisted by the work table.

Fig. 7 is a vertical section on line 7—7 in Fig. 6.

Fig. 8 is a front elevation of the stapling mechanism, showing the front plate of the casing removed to bring into view the staple driver and staple former and other elements of the mechanism by which the staples are formed and driven.

Fig. 9 is a perspective of the staple driver and staple former locked together for downward movement to form the staple.

Fig. 10 is a perspective of the unitary staple driver, pivoted latch for the staple former, spring pressed rod for the staple former, and guiding link therefor.

Fig. 11 is a perspective of the reversible staple former.

As thus illustrated, my invention comprises a stapler body A for supporting the stapling head B (of any suitable character) at the outer end thereof. The said body is supported by an upright or post-like portion C, which latter is suitably supported at its lower end. The horizontally disposed table D is pivotally supported on the post C at d, and has an adjusting screw e which bears against the post C to raise and lower the said table, this adjustment being about a horizontal axis provided by the pivotal connection d, or by any suitable means. A springy or resilient plate E, having its outer

edge curled or rolled up at α to give it stiffness at this side (the other edge being left flexible), is supported in any suitable manner upon the pivoted bracket F of the table. 5 This plate E extends forward to the front edge of the table, the inner edge G of this plate being straight and located in the horizontal plane of the body portion thereof. The outer end of this plate E is provided 10 transversely, on the under side thereof, with a bar H, this bar having its outer edge provided with an upper rib h to which the said plate is secured. This provides a space or 15 guide channel I between the said bar and plate for the feeding of the materials to the stapler, the flexible end portion i of said bar being disposed below the stapler and provided with an anvil J for clinching the staple. The receiving end of said bar H is 20 substantially even with the side edge e of the sheet-metal plate E, so that the insertion of the work will be facilitated. Also, the plate E has sufficient width to insure the required stiffness. A guide is secured by 25 brackets k to the top of the plate E at the front end thereof, this guide K having a curved top wall which extends gradually downward from a point some distance above the curved portion e of said plate, and which 30 finally extends at its other end below the stapler head B. The vertical wall of this guide K is fastened in any suitable manner to the brackets k, and the latter are secured upon the plate E by any suitable means. 35 The top of the table D is provided with adjustable gages L which engage one edge of the materials when the latter are moved through the machine to receive the staples.

Referring to Fig. 5, the carton to be made 40 comprises a blank formed with sections 1, 2, 3 and 4 which form the sides of the carton, and with a flap 5 which is stapled upon the inner surface of the side wall section 1 in the manner shown. The flaps 6 at the open 45 ends of the carton are foldable to close the latter. The machine shown and described is, therefore, for the purpose of inserting the staples 7 to connect together the two ends 50 of the foldable blank. This is done by inserting the said blank in the manner shown in Figs. 2 and 3, it being observed that the flap 5 is inserted in the guide channel I, and that the side wall section 1 rests on the plate E and slides under the guide K as the carton blank is pushed forward to bring the 55 two overlapping portions 1 and 5 ultimately into direct contact with each other at a point directly below the stapler. As the blank moves forward the staples 7 are inserted and 60 clinched on the anvil J in a manner that will be readily understood. Thus, and with the arrangement shown, the carton blank travels from right to left across the front of the machine, and during the insertion of the 65 staples the flexible portion i of the bar H is

bent downward against the table D, it being understood, however, that the lower portion of the carton blank is between this bar and said table at this time. The plate E being also more or less resilient, it follows that 70 the devices thus provided for guiding the carton blank to the stapler are adapted to yield readily to the pressure of the stapler, by the torque of said plate E resulting from the torsional strain imposed thereon by the 75 pressure of the stapler on the end of the guide H, whereby the work is solidly and firmly supported by the table below during the stapling operation. But after the insertion of each staple, the guiding bar, etc., 80 by the reverse torque movement of said plate E, will then spring upward to allow the carton blank to be fed freely forward for the next staple.

Furthermore, and inasmuch as the plate 85 E is supported by the table D, or rigidly connected therewith, it follows that the up and down adjustment of this table will not vary the distance between its top and the bottom of the bar H and that no separate 90 adjustment of this bar is necessary for different positions of the table. In other words, the table D is adjusted to meet the requirements and the guiding devices automatically maintain themselves in proper 95 relation to the other elements. In this way, and by using a table support for the guiding devices, instead of a body support therefor, the guide bar H is not only yieldingly supported in a proper manner, but in addition there is clearance at all points above the plate E, as there is no connection between the bar and the stapler head or body. Consequently, as stated, there is clearance 100 everywhere below the stapler and above the 105 said guide bar.

As shown in Figs. 4 and 8 to 11 inclusive, the stapling mechanism is as follows: The driver U is reversible end for end and is mounted on the back u which slides up and 110 down in the frame or guideway W and which is connected by a link 8 with the crank pin 9 on the crank plate m of the shaft M. A latch 10 is pivoted on the front of said back u and is provided with a spring 115 11 which connects its upper end with the upper end of the back u, or directly with the head 12 of the pivot for said link. The back or driver body u is cut away at one edge thereof to form a recess for the compression spring 13 which is mounted on the rod 14, whereby the latter is movable up and down and is yieldingly held in position by said spring. The staple former X is also reversible end for end, when it is desired 120 to change the length of the staples, and is cut away at α on the rear side thereof to accommodate the lower portions 15 of the driver back or body, being also provided 125 with guides 16 in which the driver U slides 130

up and down. The pin 17 on the front of the said staple former slides up and down in the groove 18 in the front plate of the casing of the stapler, this plate being pivoted at its upper end 19, to swing outward at its lower end. The back of the driver body is also provided with a cam 20 for operating the pivoted member Y upon which is mounted the anvil y that cooperates with the staple former to produce the staples. It will be seen that this anvil has a narrow slot 21 through which the wire is fed, and it will be understood that the lower end of the staple former X then comes down and embraces the said block or anvil y to form the staple in the usual and well known manner. As soon as the driver U strikes the top portion 22 of said anvil, the cam 20 then releases the member Y, allowing the latter to tilt and carry the anvil out of the path of the staple driver. A staple support 23 is pivoted at 24 upon the said anvil, and is in turn pivotally connected with the end of a rod 25 which carries a compression spring 26, to yieldingly and normally hold the said staple support in position. The other end of this rod 25 slides in the lower end of a guide 27 secured to the hub portion of the member Y, whereby the extension of said spring 26 serves to push the staple support 23 outward and into position. At the same time, however, and when the staple driver descends to insert the staple, the spring 26 is compressed to permit the support 23 to move out of the path of said driver, and in this way the latter practically wipes the staple head off from the upper edge of the support 23, in a manner that will be readily understood. The latch 10 engages the upper end of the staple former X, as shown in Figs. 8 and 9, when the staple driver and staple former start downward, whereby they are readily locked together. The lower end of the rod 14 also engages the upper end of the staple former. When the latch 10 engages the cam screw 28 at the lower end of the curve 29 in which the latch travels up and down, the staple former is unlocked relative to the staple driver, and the latter then moves downward alone, the spring 13 being compressed at this time and serving to yieldingly hold the staple former upon the work to form a guide for the insertion of the staple. When the staple driver and former move upward the spring 13 then expands and moves the staple former downward on the body of the driver, and the latch 10 is again brought into locking position by the spring 11, whereby the parts are again in position to move downward. It will be seen that the anvil y is held in place by a single screw 30, and that its other end is provided with a slot 31 similar to the slot 21, and also with a recess 32 for the support 23 when the anvil is reversed or turned end for end. In this way the staple driver and the staple former are reversible to vary the length of the staples, and the anvil y is accordingly reversible, it being observed that the other parts operate in the desired manner regardless of whether the staple driver and staple former and anvil are turned in one direction or the other. In other words, the latch 10 will operate with either end of the staple former, and the pivoted staple support 23 will work on either end of the anvil y, and thus variations in the thickness of the carton blank are easily taken care of without substituting other parts in the machine.

The invention is not limited, of course, to the exact construction shown and described. What I claim as my invention is:

1. A machine for stapling together the overlapping corner portions of a carton blank, to form a carton which is stapled along one corner and open at both ends thereof, comprising a guide-bar for supporting said overlapping portions and for guiding the folded blank into position for stapling, means on said bar to clench the staples, a table below said guide-bar, a stapler above said clenching means, a wide flexible plate of sheet-metal extending toward the front of the machine at one side of said stapler and provided with an end portion to extend between said overlapping portions to yieldingly support said bar, so that pressure of the stapler on said bar imposes a torsional strain on said plate, a device on said plate to engage the edge of the upper overlapping portion, one side edge of said plate being substantially even for its full length with the receiving end of said guide-bar, and means out of line with said stapler to support said plate a distance back from said guide-bar, so that torque of said plate permits said guide-bar to move downward until supported by said table, said means being disposed below the plane of said plate and in rear of the area to be covered by the blank.

2. A machine for stapling together the overlapping corner portions of a carton blank, to form a carton which is stapled along one corner and open at both ends thereof, comprising a guide for supporting said overlapping portions and for guiding the folded blank into position for stapling, means on said guide to clench the staples, a table below said guide, a stapler above said clenching means, a flexible plate of sheet-metal extending toward the front of the machine at one side of said stapler and provided with an end portion to extend between said overlapping portions to yieldingly support said guide, so that pressure of the stapler on said guide imposes a torsional strain on said plate, a device on said plate to engage the edge of the upper overlapping portion,

said plate extending above the folded blank to form a covering under which the blank must be inserted to enter said guide, and means out of line with said stapler to support said plate a distance back from said guide, so that torque of said plate permits said guide to move downward until supported by said table, said means being rigidly secured to the rear edge portion of said table, and said plate having one side edge thereof stiffened and the other relatively flexible.

3. A machine for stapling together the overlapping corner portions of a carton blank, to form a carton which is stapled along one corner and open at both ends thereof, comprising a guide for supporting said overlapping portions and for guiding the folded blank into position for stapling, means on said guide to clamp the staples, a table below said guide, a stapler above said clenching means, a flexible plate of sheet-metal extending toward the front of the machine at one side of said stapler and provided with an end portion to extend between said overlapping portions to yieldingly support said guide, so that pressure of the stapler on said bar imposes a torsional strain on said plate, a device on said plate to engage the edge of the upper overlapping portion, said plate extending above the folded blank to form a covering under which the blank must be inserted to enter said guide, and means out of line with said stapler to support said plate a distance back from said guide, so that torque of said plate permits said guide to move downward until supported by said table, and a gage disposed on said table in front of said means to engage the rear folded corner edge of said blank, one corner portion of said plate being turned up to facilitate the insertion thereunder of one portion of the work.

4. A machine for stapling together the overlapping corner portions of a carton blank, to form a carton which is stapled along one corner and open at both ends thereof, comprising a guide bar for supporting said overlapping portions and for guiding the folded blank into position for stapling, means on said bar to clamp the staples, a table below said guide bar, a stapler above said clenching means, a plate extending toward the front of the machine, and having an end portion to extend between said overlapping portions to yieldingly support said bar, a device on said plate to engage the edge of the upper overlapping portion, and means to support said plate at right angles to said bar, at one side of said stapler, the outer edge of said plate being turned upward to form a stiffening flange and provide a guide for the insertion thereunder of the lower overlapping portion.

5. A machine for stapling together the

overlapping corner portions of a carton blank, to form a carton which is stapled along one corner and open at both ends thereof, comprising a guide for supporting said overlapping portions and for guiding the folded blank into position for stapling, means on said guide to clamp the staples, a table below said guide, a stapler above said clenching means, a flexible plate of sheet-metal extending toward the front of the machine at one side of said stapler and provided with an end portion to extend between said overlapping portions to yieldingly support said guide, so that pressure of the stapler on said guide imposes a torsional strain on said plate, a device on said plate to engage the edge of the upper overlapping portion, said plate extending above the folded blank to form a covering under which the blank must be inserted to enter said guide, and means out of line with said stapler to support said plate a distance back from said guide, so that torque of said plate permits said guide to move downward until supported by said table, and a gage disposed on said table in front of said means to engage the rear folded corner edge of said blank, one corner portion of said plate being turned up to facilitate the insertion thereunder of one portion of the work.

6. A stapling machine comprising a staple driver, a back for said driver, rigidly secured thereto, a pivoted lock on said back, a spring pressed rod on said back, a link pivoted on the upper end of said back, all of said elements being removable together as a unit, a staple former engaged by said lock and rod, and means co-operating with said staple former to make the staple.

7. A stapling machine comprising a staple driver, a back for said driver, rigidly secured thereto, a pivoted lock on said back, a spring pressed rod on said back, a link pivoted on the upper end of said back, all of said elements being removable together as a unit, a staple former engaged by said lock and rod, and means co-operating with said staple former to make the staple.

8. A stapling machine comprising a staple driver, a back for said driver, rigidly secured thereto, a pivoted lock on said back, a spring pressed rod on said back, a link pivoted on the upper end of said back, all of said elements being removable together as a unit, a staple former engaged by said lock and rod, and means co-operating with said staple former to make the staple, said back being cut away at one edge thereof to accommodate said rod, and said lock and link being disposed respectively at front and rear of said back.

9. A stapling machine comprising a staple driver, a back plate for said driver, and a staple former having a groove for said driver, the rear side of said former being cut away at the center to form a recess, and said back plate having its lower end provided with shoulders at opposite sides of the driver and working up and down in said recess to lift said staple former.
10. 10. A stapling machine comprising a staple driver, a back plate for said driver, and a staple former having a groove for said driver, the rear side of said former being cut away at the center to form a recess, and said back plate having its lower end provided with shoulders working up and down in said recess to lift said staple former, said former being reversible and having a pair of lifting shoulders and a pair of staple forming portions at each end thereof.
11. A stapling machine comprising a staple driver, a back plate for said driver, and a staple former having a groove for said driver, the rear side of said former being
- cut away at the center to form a recess, and 25 said back plate having its lower end provided with shoulders at opposite sides of the driver and working up and down in said recess to lift said staple former, said back plate having a spring to hold the staple 30 former normally upon said shoulders.
12. A machine comprising a staple driver, a back plate for said driver, rigidly fixed thereto, a staple former, and means including a spring in said back plate to yieldingly 35 hold said former in position, said back plate having one side edge thereof cut away to accommodate said spring, so that said spring is disposed for expansion and contraction between two portions of said back, which portions are at opposite ends of said spring, the arrangement being such that said means are in the plane of said back plate.

Signed by me at Chicago, Illinois, this
10th day of July, 1915.

EDWARD CRAIG.
